UNITED STATES PATENT OFFICE

162,844

WINDOW SILL

Robert L. Klein, Rochelle Park, N. J.

Application September 1, 1950, Serial No. 12,018

Term of patent 14 years

(Cl. D54—2)

To all whom it may concern:

Be it known that I, Robert L. Klein, a citizen of the United States, residing at Rochelle Park, in the county of Bergen and State of New Jersey, have invented a new, original, and ornamental Design for a Window Sill, of which the following is a specification, reference being had to the accompanying drawing, forming part thereof.

The figure represents a perspective view of the window sill, showing my new design.

I claim:

The ornamental design for a window sill, as shown.

ROBERT L. KLEIN.
